UNITED STATES PATENT OFFICE

133,983

DESIGN FOR BRIC-A-BRAC

John J. Cruise and Elmer G. Anderson, Hatboro,
and Sigurd Forsmark, Philadelphia, Pa.

Application April 7, 1942, Serial No. 106,486

Term of patent 14 years

To all whom it may concern:

Be it known that we, John J. Cruise and Elmer G. Anderson, citizens of the United States, and Sigurd Forsmark, a citizen of Sweden, residing at Hatboro, in the county of Montgomery, and Philadelphia, in the county of Philadelphia, State of Pennsylvania, respectively, have invented a new, original, and ornamental Design for a Bric-a-Brac, of which the following is a specification, reference being had to the accompanying drawing, forming part thereof.

Figure 1 is a front elevational view of a bric-a-brac showing our new design.

Figure 2 is a side elevational view, and
Figure 3 is a top plan view.

We claim:

The ornamental design for a bric-a-brac, as shown.

JOHN J. CRUISE.
ELMER G. ANDERSON.
SIGURD FORSMARK.
